US00D871481S

(12) **United States Design Patent** (10) Patent No.: **US D871,481 S**
(45) Date of Patent: **** Dec. 31, 2019**

(54) **IMAGE CAPTURE DEVICE**

(71) Applicant: **Google LLC**, Mountain View, CA (US)

(72) Inventors: **Michael Robert Arens**, San Francisco, CA (US); **John Lapetina**, San Francisco, CA (US); **Peter Michael Cazalet**, Los Gatos, CA (US); **Joshua Randall Clyne**, Santa Clara, CA (US); **Kai S. Yick**, Mountain View, CA (US); **Eva Ariella Siobhan Snee**, Seattle, WA (US); **Jade Daniel Moreau**, Mountain View, CA (US); **Philip Dam Roadley-Battin**, Oakland, CA (US); **Jonathan Yoshida Rowell**, New York, NY (US); **Kenneth Sweet**, San Francisco, CA (US); **Jason Pi**, San Jose, CA (US); **Aaron Michael Donsbach**, Seattle, WA (US); **Juston Payne**, San Mateo, CA (US); **Maj Isabelle Olsson**, Sunnyvale, CA (US)

(73) Assignee: **Google LLC**, Mountain View, CA (US)

(**) Term: **15 Years**

(21) Appl. No.: **29/680,967**

(22) Filed: **Feb. 21, 2019**

CLAIM

The ornamental design for an image capture device, as shown and described.

DESCRIPTION

FIG. 1 is a front perspective view of a first embodiment of an image capture device showing our new design;
FIG. 2 is a rear perspective view thereof;
FIG. 3 is a front view thereof;
FIG. 4 is a rear view thereof;
FIG. 5 is a side view thereof;
FIG. 6 is an opposite side view of thereof;
FIG. 7 is a top view thereof;
FIG. 8 is a bottom view thereof;
FIG. 9 is a front perspective view of a second embodiment of an image capture device showing our new design;
FIG. 10 is a rear perspective view thereof;
FIG. 11 is a front view thereof;
FIG. 12 is a rear view thereof;
FIG. 13 is a side view thereof;
FIG. 14 is an opposite side view thereof;
FIG. 15 is a top view thereof; and,
FIG. 16 is a bottom view thereof.

(Continued)

The broken lines depict portions of the image capture device in which the design is embodied that form no part of the claimed design.

1 Claim, 14 Drawing Sheets
